GARMENT FOR LONG-EARED DOGS

Ruth F. McCaleb, Evanston, Ill.

Application April 4, 1938, Serial No. 199,745

6 Claims. (Cl. 54—80)

My invention contemplates and provides coverings to be worn by a long-eared dog, e. g., a cocker spaniel or springer spaniel, to protect its ear hair from contact with mud, burs, its food, etc.

The object of the invention is to provide such coverings which may be (a) easily and securely applied to a dog, (b) comfortably worn by the dog, (c) readily laundered, or otherwise cleaned, and (d) economically manufactured.

In the hereinafter described embodiment of my invention, the ear coverings are in the form of pockets wherein and wherewith the ears of the dog may hang and swing more or less naturally, such pockets forming portions of a unitary garment which preferably is formed, wholly or as to its pocket portions, of a strong textile fabric such, for example, as canvas.

These and other features, objects and advantages of my invention will appear from the following description wherein reference is made to the accompanying drawing, in which

Fig. 1 is a view in perspective which illustrates the ear covering garment being worn by a long-eared dog of one of the species for which such garment is intended;

Fig. 2 is a plan view of the garment;

Fig. 3 is a vertical sectional view of the garment when draped to substantially the configuration which it takes while being applied to the dog; and

Figs. 4 and 5 are cross sectional views taken, respectively, on lines 4—4 and 5—5 of Fig. 2.

Similar characters of reference refer to similar parts throughout the several views.

The ear covering garment desirably comprises a single piece of flexible material, e. g., a strong textile fabric such as canvas, which is so shaped, edgebound, folded and stitched upon itself, as to define the two pockets 6, the pocket suspending web 7, and the throat flaps 8. To the tip of each flap 8 may be attached a tie-tape 9.

When the garment is formed largely from a piece of canvas or other textile fabric, its edges are preferably embraced by and stitched to a suitable binding tape 10. The folds 11 provide the bottoms of the pockets 6, and the sides of the pockets conveniently are closed by additional binding tapes 12.

When the garment is worn by the dog, as illustrated in Fig. 1, the dog's ears hang down in the pockets 6 which are suspended from the top and/or back of the dog's head by the web 7, such web amounting to an extension of the outer wall of each pocket. The throat flaps 8, which

amount to extensions of the inner walls of the pockets, are then crossed at the dog's throat and their respective tapes 9 are carried around the dog's neck to be tied together at the back of the neck, as indicated at 13 in Fig. 1. Thus the 5 garment is held on the dog in such manner that the dog cannot dislodge it with teeth or paws or by dragging the bottoms of the pockets against the surface over which the dog is traveling.

The means for holding the crossed flaps 8 in 10 position, with respect to the dog's neck and each other, may be in the form of fastening instrumentalities other than the tapes 9. However, I prefer to employ tie-tapes for such purpose.

Instead of being made largely of canvas, the 15 garment may be formed, either wholly or partially, of water-proof material.

The garment usually is colored to correspond or blend with the coat of the dog to which it is applied. However, when the garment is applied 20 to a hunting dog, it is usually of a bright red color, for the same reason that deer hunters advisedly wear red garments.

What I claim is new and desire to secure by Letters Patent of the United States is:

1. A garment for a long-eared dog comprising a pair of upwardly opening flexible pockets, in which the dog's ears may hang and swing naturally, a flexible web connecting the upper portions of the outer sides of the pockets and adapted to be extended over the dog's head, and flexible fastening means, connected with the upper portions of the inner sides of the pockets, adapted to be crossed in the vicinity of the throat and to be tied together at the back of the neck. 35

2. A garment, arranged to fit on and be supported by the head of a long-eared dog, provided with upwardly opening flexible pockets for the reception of the dog's ears, said pockets having the upper portions of their outer sides connected by a supporting web arranged to extend over the dog's head to carry the pockets in their appropriate ear-receiving positions. 40

3. A garment for a long-eared dog comprising a pair of pockets for receiving the dog's ears, 45 means connecting the pockets adapted to be extended over the dog's head to support the pockets in ear-receiving positions, and fastening means connected with the pockets and adapted to be overlapped at the throat. 50

4. A garment, arranged to fit and be supported by the head of a long-eared dog, provided with pockets in which the dog's ears may hang and swing naturally.

5. A garment for a long-eared dog comprising 55

a pair of upwardly opening ear-receiving pockets in which the dog's ears may hang and swing naturally, flexible means connecting the upper portions of the outer sides of the pockets, and flexible 5 fastening means connected with the upper portions of the inner sides of the pockets.

6. A garment for a long-eared dog comprising a pair of upwardly opening flexible pockets for

the reception of the dog's ears, a flexible web connecting the upper portions of the outer sides of the pockets and adapted to be extended over the dog's head, and flexible fastening means arranged to extend between the pockets and under the dog's throat. 5
